UNITED STATES PATENT OFFICE.

WALTER E. SAWTELL, OF LONDON, ENGLAND.

DARNING MACHINE.

1,427,023.

Specification of Letters Patent. Patented Aug. 22, 1922.

Application filed July 26, 1920. Serial No. 399,112.

To all whom it may concern:

Be it known that I, WALTER EDWARD SAWTELL, a subject of the King of Great Britain, residing in London, England, have invented 5 certain new and useful Improvements in Darning Machines, of which the following is a specification.

My invention has for its object the production of a hand or foot operated darning 10 machine that is compact, portable and capable of knitting a piece of fabric or a patch on to a sock or other article of knitted or woven fabric, or into a hole or a tear therein, thereby darning or repairing, or ornamenting same.

A machine embodying my invention comprises, as is customary in knitting machines, a base piece carrying a frame that supports a row of aligned bearded or latch needles 20 mounted on a suitable rising and falling block or holder, a travelling yarn or thread carrier fed from a spool mounted on the frame, a series of sinkers adapted to pass to and fro between the needles when these 25 are depressed so as to loop the yarn about the needles, means for closing at the proper time the needle beards so as to cause them to retain the yarn and to permit them to return through the fabric and previously 30 formed loops, an appliance for holding the work or the material of the article to be operated on, and means for feeding relatively to the row of needles with a step by step movement.

35 I will describe my invention with reference to the accompanying drawings, which show one arrangement of a darning machine constructed according to the invention.

40 Fig. 1 in the drawings is a side elevation, and Fig. 2 a front elevation of the machine, the needle block being in a position somewhat above that which it assumes at the lower end of its stroke; Fig. 3 is a rear 45 elevation of the same; Fig. 4 is a longitudinal vertical section on line IV—IV Fig. 3; Fig. 5 is a vertical section along the line V—V in Fig. 1; Fig. 6 is a plan of a set of cams and the sinkers operated thereby, the needles being shown in section; Fig. 7 is a perspective view, to an enlarged scale of a yarn carrier paying out yarn in front of the sinkers and behind the needles, the beards on the latter being open; Fig. 55 8 is a perspective view, to an enlarged scale, showing some of the sinkers indicated in

Fig. 7 pushing yarn between the needles, the beards being open; Fig. 9 is a view showing in elevation the front ends of some of the sinkers and some of the needles in the act of 60 rising and thereby drawing yarn through the piece of work to be darned, and Fig. 10 is a view similar to Fig. 7 showing the sinkers advanced by the cams to the full extent, the yarn loops formed by the forward movement of the sinkers, the yarn being engaged by the beards on the needles which are closed.

In the drawings, 1 denotes a base piece on which is mounted the main frame 2 that 70 carries the knitting or darning mechanism and part for operating same as described below. 3 is a rising and falling block carrying an aligned row of interchangeable bearded needles 4 which, as here illustrated, are eight in number. 5 is the yarn or thread carrier which is fed with yarn or thread 5' from a spool 6. A number of sinkers, nine in all, for forming loops in the yarn and arranged side by side are indicated by the numeral 7. On each side of the series of sinkers 7 is one which I call an outside sinker or yarn guide 7', provided for a specific purpose which is described hereinafter and is other than that for looping the yarn about the needles.

For intermittently closing the beards 4' of the needles 4 as they pass upwardly through the loops formed about them by the movement of the sinkers 7 after the needles have 90 made their downward stroke, a slideable bevelled edge bar 8 is provided. This bar is mounted to slide in guideways provided for the purpose on the frame 2 and is attached to a pair of rearwardly extending 95 actuating arms 9 by which it is reciprocated by mechanism referred to below, and in proper timed relation with the rising movement of the needles.

Fitted to or projecting from the front of 100 the frame 2 is an auxiliary frame or horn 10 on which is slidably mounted a work carrier or shield 11, which constitutes a cover above the sinkers. The shield is seen in Figs. 1, 4 and 5, but in the latter figure 105 part of it is shown broken away. The horn and shield together are made such a size that the smallest sock or tubular article that the machine is intended to deal with can be fitted around or slipped on to 110 them. In order to prevent the frayed edges or tongues of a tear or worn hole in the

article or fabric 12 to be darned, from rising as the needles move upwardly through the same and to facilitate the entry and passage of the beards 4' of the needles 5 through existing portions of the fabric, I provide a device 13, which I hereafter term a presser foot that is pivotally mounted on the lower end of a vertically reciprocating frame 14, which is intermittently raised 10 together with the presser foot 13, to allow of the feeding movement of the fabric or work 12 along the horn. In order that the presser foot may be retained in a vertical or operative position, it may be provided 15 with latches or other suitable devices, not shown, for locking it in alignment with its frame or holder 14.

By reason of the ratio of the travel of the 20 yarn or thread carrier 5 laterally of the last needle in the row, Fig. 10, to the height or depth between the face of the fabric being darned, and the level at which the yarn or thread leaves the carrier being small as compared with the corresponding ratio in 25 known knitting machines, it is necessary to provide means to retain the yarn, when the yarn carrier commences each of its strokes in directions parallel with the row of needles at such a level that the yarn issuing from the 30 carrier will be in a position for the head of the sinkers 7 when moving to the front or forward positions, to engage with it. For this purpose I provide the two end or outside sinkers 7', which are auxiliary sinkers 35 and are not used for forming loops with means for retaining the yarn in the desired position. Such means may consist in forming a suitably shaped notch 7², Figs. 7 and 10, on the front end or on the top edge, or 40 in both places, of each of the said outside sinkers and causing these two sinkers alternately to dwell in the forward position until such time as one or more of the other sinkers 7 have been advanced between the needles 4 45 to the forward position. To this end the two outer sinkers or yarn guides 7' are operated or shifted independently of the sinkers 7 as explained below.

To assist in retaining the yarn in the front 50 notches 7² during the periods of dwell, suitable springs 7³ fixed at one end to a plate 10' attached to the front end of the horn 10, may be arranged to bear against the front ends of the sinkers 7' while these are in 55 their advanced positions during such periods, as shown in Fig. 10.

To assist in retaining the yarn in position on the heads of the sinkers, the head of those sinkers that are next adjacent to the outside 60 sinkers 7' may be provided with notches 7⁴. If desirable, the heads of the other sinkers may also be notched.

The needle block 3 is detachably connected with a carrier 15 that is adapted to reciprocate on a vertical dovetail guideway 16, and

has a projection 15' that is detachably connected by means of linkage 17, 17' with one end of a rocking lever 18 pivotally mounted between its ends at 18' on uprights 19 supported on the frame 2.

The linkage 17, 17' is adapted to be adjusted in length in any suitable way, for instance, the member 17 may be made tubular and internally screwthreaded at its upper end, and the part 17' may be similarly 75 threaded and engaged for a greater or less length in the part 17. The linkage is made adjustable in length in order that the length of the up and down travel of the needleblock and needles may be regulated according as 80 the loops to be formed with the yarn, as hereinafter explained, are to be long or short loops.

It is preferred to make the part 17' readily 85 detachable from the lever 18, and a convenient mode of connecting these two members is shown in Fig. 2. A tubular casing 55 is attached to the side of the lever and adapted to slide therein is a spring-pressed plunger pin 55' which passes through eyes in the 90 forked end of the lever and the upper end of the part 17'. The plunger pin is provided with an arm 56 which extends through a curved slot 57 formed in and extending lengthwise of the casing 55. The spring 59 95 interposed between the plunger pin and a cover 58 on the end of the casing normally keeps the plunger pin in the position wherein it extends through eyes provided in the forked end of lever 18 and the part 17'. 100 By moving the arm 56 along the slot against the action of the spring 59, the pin may be withdrawn to disconnect the part 17' from the lever end.

The lever 18 is adapted to be rocked by 105 means of the links 20 and 20' depending from its other end, the latter sliding in dovetail guide 20² carrying a bowl 20² that receives motion from a cam member 21 on a cam shaft 22 that is rotated by 110 means of suitable gears 23, 24 and 25 from a flywheel shaft 26, that can be operated by hand or by means of pedal mechanism. In Fig. 3 a flywheel 26' having a crank handle (shown broken away in the 115 figure) is provided for turning the shaft 26.

Any appropriate means may be provided for locking the needle block in elevated position when it is released from its rocking lever, for adjusting or other purposes, but 120 such means is not shown in the drawings.

The nine sinkers 7 shown in the drawings, are moved in the forward direction towards the needles 4 by nine separate cams 27, a cam for each sinker. The cams are mounted on 125 a counter shaft 28 that is preferably supported in bearings that are adjustable in position relatively to the frame for the purpose of varying the length of the forward stroke of the sinkers 7 so as to alter the 130

length of the loops 5² (Fig. 10) formed by their aid. To this end the shaft 28 may be journalled in a sliding carriage 29, which may be shifted backwards or forwards by 5 means of the regulating screw 30, the frame being slotted at 2' to permit the adjustment.

The cams are so fashioned that the sinkers will be operated by them in succession one after the other. The return of the sinkers 7 10 in the reverse direction to the rear position may be effected by means of springs, or weights, or by appropriate positively acting appliances. In the arrangement shown in the drawings, a series of springs 31, one for 15 each sinker, is employed for this purpose. The springs are attached at one end to a sinker and at the other end to the frame 2. The outside sinkers 7' may be similarly operated, cams 27' being provided for moving 20 the said sinkers forward and springs similar to springs 31 for returning them.

The counter shaft 28 may be conveniently turned by means of a gear wheel 32 thereon, and in mesh with the gear wheel 23 on the 25 cam shaft 22. Discs 27² are preferably arranged between the sinker cams or the cams are provided with side flanges to serve as guides to the inner ends of the sinkers as these latter move to and fro.

30 The yarn or thread carrier comprising a head 5 and a shank 5³ is mounted on a slide 33 which is reciprocated along a guide bar 34 suitably supported on the frame 2, in directions parallel with the row of needles 35 by means of a lever 35 that is connected at one end by a link 35' with the slide and at the other end to a part 36 fixed to the frame 2, and is adapted to be rocked by a member 37 carried by the lever and arranged to take 40 into a groove 38' on a cam member 38 mounted on the cam shaft. Other suitable mechanism, however, may alternatively be employed for reciprocating the slide 33, in lieu of that just described.

45 The movement of the frame 14 carrying the presser foot 13 can be effected by means of suitable lever mechanism such as that which is shown in Figs. 1-4 and which comprises the U-shaped lever 39 pivoted at 39' on the support 40 carried by the frame 2. The lever 39 has a rearwardly extending arm 39² to which is adjustable and pivotally connected one end of a link 41 which at its other end is pivotally connected 50 with an end of a two armed lever 42 pivoted between its ends at 42' on the frame 2. The other end 42² of lever 42 is arranged to lie in the path of travel of two pins 23' projecting laterally from a face of the wheel 23. The upper end of the presser foot frame 60 14 is connected with the lever 39 by a pin or rod 44 that is slidably in a slot 39³ provided in the front end of the lever.

A spring 45 attached at one end to the 65 frame 2 and at its other or upper end to the

front end of lever 39 tends to keep the said front end, the frame 14 and the presser foot 13 depressed. When the machine is in operation and wheel 23 revolves, the pins 23' intermittently engage the end 42² of the 70 lever 42, and cause said lever to turn on its pivot 42' thereby operating the parts 41, 39, 43 and 14 so that the presser foot 13 is momentarily raised to allow of the forward feed of the material to be darned. 75

The needle beard closing mechanism, which as stated above comprises the bevelled edge bar 8 that is disposed transverse of and in rear of the row of needles 4, is intermittently reciprocated by link and lever mechanism controlled by a cam device carried by the cam shaft 22. Such mechanism may comprise a spindle 46 that is journalled in the side wall of the horn 10 and is provided at each end with an arm 46' the two arms being pivotally connected respectively with parts 9' depending from the ends of the two arms 9 for actuating the beard closing bar 8. A third arm 46² on the spindle 46 is pivotally connected with the lower end of 80 a link 47 which at its other end is pivotally connected with a lever 48 which is pivoted between its ends at 48' on the frame 2, and carries at its upper end a bowl or other member 49 which is normally pressed by the 85 action of a spring 50 into engagement with the periphery of the cam member 21 on cam shaft 22, the said periphery being provided with two projections 21' which on engaging with the bowl 49 as the cam member rotates 90 100 will cause lever 48 to turn about the axis of its fulcrum 48' and cause the arms 9 and beard closing bar 8 to advance and close the beards on the needles 4.

The work holder may be arranged to slide 105 or be fed along the horn either automatically by spring action or positively by appropriate step by step feed mechanism actuated from one or other of the shafts.

In the machine illustrated, particularly in 110 Figs. 1, 2, 3 and 5 of the drawings, a suitable step by step feed mechanism is shown, the mechanism comprising an inverted U-shaped plate 51 furnished on its face with a series of teeth or points 51' adapted intermittently to engage with, and when rocked in the manner described below, to retract from off the shield or carrier 11, for a predetermined extent, the material 12 that is being darned. The plate 51 has on each of 115 its side limbs a slot 51² into which projects a pin 52 extending laterally from the side of a bar 52' carried by the plate 10'. The two auxiliary sinkers 53 one on each side of the machine are advanced forwardly by two 120 flanged cam members 54 against the action of springs 53' attached to the sinkers 53 at one end and to the frame 2 at the other end. The sinkers 53 are returned rearwardly as 125 the cam member permits by the springs 53'. 130

In the front side portions of the sinkers are grooves 53² and into these grooves project pins 51³ on the limbs of plate 51. The grooves are so designed that, as the sinkers 53 reciprocate, combined up and down and oscillatory movements are imparted to the toothed plate 51 by the cooperative action between the grooves and the pins 51³. As the sinkers advance beyond the position 10 shown in Fig. 1, while the teeth 51¹ engage with the material 11 the upper part of plate 51 will rock forwardly, the plate turning about pins 52, and the said upper part thereby retracting or drawing the material 15 along with it. As the sinkers return or move rearwardly the plate 51 will be drawn down and be simultaneously rocked back to the upright position, the teeth being simultaneously retracted from the material. When 20 next the sinkers 53 advance the plate 51 will be again raised so that the teeth re-engage with the material and the positions shown in Fig. 1 are again attained.

Supposing the machine is to be utilized for 25 repairing or darning a hole in a sock or other piece of fabric, its action is as follows:—

Yarn or thread from spool 6 is threaded through a guide 33' carried by the slide 33 and through an eye in the front end 5 of the 30 yarn carrier. The sock is then drawn over the shield 11 and horn 10 as indicated in Fig. 2, or in the case of a piece of fabric, the fabric is stretched or spread on to the shield 11, the hole in the sock or piece of fabric being arranged in the rear of the row of 35 needles. The presser foot 13 which would have been turned on its pivots to permit of the work being adjusted in position is then turned back and lowered to hold the sock or 40 fabric down. On the flywheel shaft 26 being turned, the needles 4 descend through the fabric 12, the yarn or thread 5' is carried across (from right to left in Figs. 2 and 7) and below the bottom face of the sock or 45 fabric on the shield 11 in the space between the front ends of the sinkers and the rear portions of the needles. On the sinkers 7 advancing, the yarn is carried or pushed by them through the spaces between the needles, 50 whereby a set of loops 5² is formed as shown in Fig. 8.

The beards 4' of the needles are thereupon closed by the beard-closing bar 8, the yarn being then retained by the needles which rise 55 and take the loops 5² through the sock or fabric, Fig. 9, whereupon the presser foot rises to release the work which is then drawn forward by the action of the toothed plate 51 as explained above.

60 The needles having in their ascent thus passed through the fabric the beards are relieved from pressure by the beard-closer so that on the needles again descending the loops are free to disengage from the beards.

65 After the descending needles have passed or

returned through the fabric the yarn is again drawn across the machine (on this occasion from left to right) in rear of the needles and a new set of loops is formed, as shown in Fig. 10, which loops, as the needles again 70 ascend are drawn through the first said set of loops. These operations being repeated, the hole in the fabric eventually becomes filled in with a series of loops. The loop filling should extend somewhat beyond the margins 75 of the hole.

The yarn should now be severed from the supply on spool 6 and the stitching or knitting continued until the end of the cut-off portion of the yarn is knitted in and the 80 work is free of the needles and consequently free to be drawn or taken off the horn.

As stated above, the size of the loops formed is governed by the extent to which the sinkers can move in advance of the 85 needles, which is regulated by the position of the sinker cams 27 on the cam shaft 28 which is carried in adjustable bearings in the sliding frame or carriage 29 that can be advanced or drawn back without the gears 90 32 and 23 employed for rotating the shaft being put out of gear.

As the loops are to be finer or coarser, the lift of the needles will be accordingly regulated by adjusting the effective length of the 95 linkage device 17 employed for connecting the needle block carrier 15 with the needle operating lever 18. A suitable index device may be provided for indicating the amount of adjustment effected in the length, which 100 adjustment should bear a proportional relation to the adjustment in position of the sinker cam shaft 28.

Having thus described the nature of the 105 said invention and the best means I know of carrying the same into practical effect, I claim:—

1. An apparatus for repairing knit material comprising a row of alined spaced bearded needles mounted for descending and rising movement, means for imparting movement to said needles to cause them to first descend through the material to be repaired and then to pass upwardly through it, a yarn carrier movable to and fro transversely of and in the rear of the row of needles for spreading yarn behind the needles and below said material, a series of independently operated reciprocating sinkers for pushing the spread yarn forwardly between and against the needles when in the lowered position and for looping the yarn about the needles, means for closing the beards of the needles to cause said beards to engage the yarn for drawing said loops through said material during the rising movement of the needles, means for reciprocating said sinkers, means for imparting a step-by-step movement to said material in a direction 110 rearwardly of and relatively to the row of 115 120 125

needles, means for holding said material yarn behind the needles and below the material to be operated upon, a plurality of independently-operated reciprocating sinker bars each movable between a pair of said needles after the needles have penetrated 35

5 nisms.

2. An apparatus according to claim 1 wherein the means for reciprocating the sinkers is adjustable for varying the field of movement of the sinkers and thereby 10 varying the size of the loops of yarn formed by said sinkers.

3. An apparatus according to claim 1 wherein the means for imparting movement to the needles may be lengthened or shortened 15 in accordance with the length of the loops of yarn formed by the sinkers.

4. An apparatus according to claim 1 wherein a pair of yarn guides are mounted to reciprocate below the plane of movement 20 of the material and to the rear of the needles.

5. An apparatus for repairing knit material comprising a holder for the material to be operated upon, a block movable toward 25 and away from said holder, a plurality of spaced bearded needles carried by said block, means for adjusting the length of movement of said block, a yarn carrier mounted to reciprocate transversely of and 30 to the rear of said needles for spreading

therefrom, means for moving the material along said holder a definite distance rearwardly of said needles each time said needles are withdrawn from said material, means for holding the material against movement 50 while the needles are penetrating same and are being withdrawn therefrom, means for adjusting the length of movement of said sinker bars, and means for actuating said block, yarn carrier, yarn guides, sinker bars, 55 beard closing means, work moving means and work-holding means in timed relation.

In testimony whereof I have signed my name to this specification.

WALTER E. SAWTELL.
